UNITED STATES PATENT OFFICE

160,847

EYE TESTING INSTRUMENT

Charles A. Ellis, Worcester, Mass., assignor to
American Optical Company, Southbridge,
Mass., a voluntary association of Massachusetts

Application January 10, 1950, Serial No. 7,134

Term of patent 14 years

(Cl. D57—1)

To all whom it may concern:

Be it known that I, Charles A. Ellis, a citizen of the United States of America, residing at Southbridge, in the county of Worcester and State of Massachusetts, have invented a new, original and ornamental Design for an Eye Testing Instrument, of which the following is a specification, reference being made to the accompanying drawings, forming a part thereof.

Fig. 1 is a side elevational view of an eye testing instrument embodying my new design;

Fig. 2 is a top plan view of the instrument shown in Fig. 1; and

Fig. 3 is a front elevational view thereof.

The characteristic features of my design reside in the portions shown in full lines in the drawings.

I claim:

The ornamental design for an eye testing instrument, substantially as shown and described.

CHARLES A. ELLIS.
